UNITED STATES PATENT OFFICE.

ROBERT C. BENDER, OF ST. LOUIS, MISSOURI.

INVOICE-HOLDER.

1,275,367.

Specification of Letters Patent. Patented Aug. 13, 1918.

Application filed February 9, 1918. Serial No. 216,198.

To all whom it may concern:

Be it known that I, ROBERT C. BENDER, a citizen of the United States, residing at St. Louis, Missouri, have invented a certain new and useful Improvement in Invoice-Holders, of which the following is a full, clear, and exact description, such as will enable others skilled in the art to which it appertains to make and use the same, reference being had to the accompanying drawings, forming part of this specification.

My invention relates to an invoice holder and particularly to the types of invoice holders disclosed in my copending applications filed July 5, 1917, Serial Numbers 178,675 and 178,676, the principal object of my present invention being to generally improve upon and simplify the constructions disclosed in said applications, and to provide a comparatively simple and inexpensive device which will hold in a convenient manner invoice sheets or record slips such as are generally used by business houses and particularly those engaged in the selling and distribution of merchandise.

Further objects of my invention are, to provide a holder to which the invoice sheets can be quickly and easily applied or from which they can be readily removed; to provide a device wherein portions of the invoice-holding means can be readily detached to permit parts of the invoice to be folded back in order to ascertain data appearing on those invoices below the uppermost invoice, and further, to provide an invoice holder which will greatly facilitate the work of the bookkeeper or clerk in keeping an accurate record of transactions between seller and buyer.

With the foregoing and other objects in view, my invention consists in certain novel features of construction and arrangement of parts, hereinafter more fully described and claimed, and illustrated in the accompanying drawings, in which—

Figure 1 is a front or face view of an invoice holder of my improved construction.

Fig. 2 is an elevational view of the rear side of the invoice holder and showing an invoice held in proper position upon said holder by means of a readily detachable retaining device.

Fig. 3 is a vertical section taken approximately on the line 3—3 of Fig. 1.

Fig. 4 is a vertical section taken approximately on the line 4—4 of Fig. 2. 55

Fig. 5 is a transverse section taken approximately on the line 5—5 of Fig. 1.

Fig. 6 is a detail sectional view showing the connections between the elastic retaining device and the body of the holder. 60

Fig. 7 is a perspective view of a portion of the elastic retaining device.

Fig. 8 is an enlarged elevational view of a portion of the body of the holder and 65 showing the index tag.

Fig. 9 is a vertical section taken on the line 9—9 of Fig. 8.

Referring by numerals to the accompanying drawings which illustrate a practical embodiment of my invention, 10 designates the body of the holder which is substantially rectangular in form and preferably constructed of sheet metal. Formed integral with the upper portions of the side edges 70 of this body 10 are upwardly and inwardly projecting lips or flanges 11, the same serving as keepers or retaining means for a card 12, which latter is provided with suitable lines and spaces upon which may be written 80 a customer's name and address, and data relative to the handling of the sales or business transacted with said customer.

Formed integral with the upper portions of the side edges of the body 10 and projecting inwardly on the rear or reverse side of the holder are ears or lips 13 which serve as retaining means for a card such as 12 when it is desired or necessary to place said card on the reverse side of the holder. The 90 side edges of the body 10 below the retaining lips or flanges 11 and 13 are bent to form marginal beads 14 which serve to reinforce and stiffen the holder.

Formed integral with the upper edge of 95 the body of the holder and preferably adjacent to the upper left hand corner thereof is a projecting portion 15 through which is formed an aperture 16 and that portion of the metal immediately adjacent to said aperture is depressed as designated by 17. Stamped from the metal on opposite sides of the opening 16 and projecting upwardly away from the recessed edge 17 are ears 18. This arrangement provides a holder 105 for a small disk 19 of cardboard or the like upon both faces of which is printed an index letter.

It will be understood that when customers' cards such as 12 are positioned on the holder, an index disk 19, bearing letters the same as the first letter of the name of the 5 customer, is positioned beneath the retaining lips or flanges 18 and thus said index tag or disk serves as a guide for the placing of the invoice holder in the proper container.

10 Formed in the left hand edge of the body 10 and at a point near the center thereof is a short inwardly extending slot 20, the inner end of which communicates with a pair of spaced notches or apertures 21. On 15 the righthand side of the body near the edge thereof is formed a pair of outwardly presented tongues 22, the same being preferably stamped from the metal forming said body 10, one of said tongues being extended upwardly above the front face of the body and the other tongue being extended downwardly with respect to the rear or underface of said body.

Formed in the lower end of the body 10 25 and preferably at a central point thereon is an inwardly projecting slot 23, the same terminating in a pair of spaced apertures or notches 24. Stamped from the body 10 immediately above slot 23 and notches 24 30 is an upwardly extending transversely disposed strap 25, the same serving as a seat for the lower end of a resilient retaining finger 26, the upper end of which is adapted to bear directly against the front face of the 35 body 10 at a point near the center thereof. This finger 26 is adapted to serve as a keeper for a limited number of invoices placed on the front side of the holder and said finger is readily detachable from the strap 25 in 40 order that it may be temporarily laid aside and replaced by an elastic retaining device, and which latter is capable of holding a comparatively large number of invoices on the holder. This elastic retaining device is composed of a pair of elastic tapes 27 and 28, the 45 same being arranged substantially at right angles to each other and held to slide freely through a keeper 29, the latter being in the form of a disk and composed of two layers 50 of fabric or the like, the edges of which between the crossed straps 27 and 28 being secured to each other by rows of stitching or in any suitable manner.

One end of the elastic tape 27 is provided 55 with a hook 30 which is adapted to engage over the upper edge of the body 10 of the holder, the opposite end of said tape being provided with a metal loop 31 from which projects a spherical or pear-shaped member 60 32 which is adapted to enter the slot 23 in the bottom of the holder 10 and occupy either one of the notches 24. One end of elastic tape 28 is provided with a metal loop 33 from which projects a spherical or pear-shaped member 34 that is adapted to enter

the slot 20 and engage in either one of the notches 21. The opposite end of this tape 28 carries a substantially triangular metal loop 35 with which is adapted to engage either one of the tongues 22.

Where my improved device is utilized for holding a comparatively small number of invoices, the elastic retaining device comprising the tapes 27 and 28 is not used, but a resilient member 26 has its lower end 70 inserted through strap 25 as illustrated in Figs. 1 and 3. A card 12 containing the customer's name, address and certain data is positioned on the front face of the holder 10 with the ends of said card positioned beneath the retaining lips 11 and an index disk 19 bearing the proper letter is inserted beneath the retaining lips 18.

As the invoices are made out, they are placed on the face of the holder beneath the 85 free end of the resilient member 26 and which latter it will be understood holds the invoices in proper position on the body 10 while the latter is being handled by the bookkeeper or clerk or while the holder is 90 temporarily placed in a proper container.

Where the device is utilized for holding a comparatively large number of invoices, the resilient member 26 is detached from the body of the holder and one of the elastic 95 retaining devices is applied to said holder with the hook 30 engaged over the top edge of said holder, the member 32 engaged in one of the notches 24, the member 34 engaged in one of the notches 21 and the loop 100 35 engaged on one of the tongues 22. To insert additional invoices beneath the elastic retainer, it is only necessary to detach hook 30 and elevate the central portion of the elastic retainer a sufficient distance to place 105 the latest on top of those already positioned on the holder. In the event that it is desired to examine any one or all of the invoices below that one on top, the member 34 110 is disengaged from the notch in which it is positioned and the righthand portions of the invoices are now free to be turned back to facilitate inspection.

By providing two tongues 22 and two sets 115 of the notches 21 and 24, it is possible to use one of the elastic retaining devices on each side of the holder, thereby materially increasing the holding capacity of the device.

An invoice holder of my improved construction is comparatively simple, can be easily and cheaply manufactured, and provides an efficient and convenient time and labor-saving device for all business houses making use of invoice sheets or the like.

It will be readily understood that minor 125 changes in the size, form and construction of the various parts of my improved invoice holder may be made and substituted for those herein shown and described, without departing from the spirit of my invention,

the scope of which is set forth in the appended claims.

I claim:

1. In a device of the class described, the combination with a plate adapted to receive invoice sheets, of an invoice sheet retaining device adapted to be removably applied to said plate, said retaining device comprising a pair of crossed elastic tapes, and plate engaging means carried by the ends of said tapes.

2. In a device of the class described, the combination with a plate adapted to receive invoices, of an invoice retaining device comprising a pair of crossed elastic tapes, securing means carried by the ends of said tapes, and portions of the plate being constructed so as to receive said securing means.

3. In a device of the class described, a plate adapted to receive invoices, and an invoice retaining device adapted to be detachably applied to said plate, said retaining

device comprising a pair of crossed elastic members, means carried by the ends of said crossed members for engaging the side and end portions of the plate, and a keeper applied to said members at their crossing point, said keeper being loosely mounted on said members.

4. In a device of the class described, the combination with a plate adapted to receive invoice sheets, of an invoice sheet retaining device comprising a pair of crossed elastic members, and means on said members for detachably engaging the sides and ends of said plate.

In testimony whereof I hereunto affix my signature in the presence of two witnesses, this 1st day of February, 1918.

ROBERT C. BENDER.
